UNITED STATES PATENT OFFICE

132,037

DESIGN FOR A BANNER OR SIMILAR ARTICLE

Archie Wilburn and Walter M. O'Neal,
Grass Valley, Calif.

Application February 4, 1942, Serial No. 105,640

Term of patent 7 years

To all whom it may concern:

Be it known that we, Archie Wilburn and Walter M. O'Neal, citizens of the United States, residing at Grass Valley, in the county of Nevada and State of California, have invented a new, original, and ornamental Design for a Banner or Similar Article, of which the following is a specification, reference being had to the accompanying drawing, forming part thereof.

The figure is a plan view of a banner or similar article, showing our new design.

We claim:

The ornamental design for a banner or similar article, as shown.

ARCHIE WILBURN.
WALTER M. O'NEAL.
